UNITED STATES PATENT OFFICE.

WILLIAM OSBORNE, OF BROOKLYN, NEW YORK.

BATHING-CAP.

SPECIFICATION forming part of Letters Patent No. 364,847, dated June 14, 1887.

Application filed March 3, 1887. Serial No. 229,570. (No model.)

To all whom it may concern:

Be it known that I, WILLIAM OSBORNE, a citizen of the United States, residing at Brooklyn, in the county of Kings and State of New York, have invented new and useful Improvements in Bathing Caps, of which the following is a specification.

This invention relates to improvements in bathing-caps, as set forth in the following specification and claim, and illustrated in the accompanying drawings, in which—

Figure 1 is a view of a cap in use. Fig. 2 is a perspective view of a cap. Fig. 3 is a vertical central section of a cap.

15 Similar letters indicate corresponding parts.

In the drawings, the letter A designates the body of the cap, formed integral with the elastic brim B, to adapt the cap to different-sized heads without puckering and thereby leaving 20 spaces through which water can enter. The brim is re-enforced by folding or doubling the material upon itself to give strength to the

device. The body A is imperforate and made of elastic water-proof material, such as rubber. The brim B is elastic, to enable the cap to 25 be fitted snugly to the head of the wearer. By this device a head-dress is obtained which is water-proof and which can be readily fitted to the head of the wearer.

What I claim as new, and desire to secure by 30 Letters Patent, is—

A head-covering for protecting the hair in bathing, consisting of the imperforate elastic body A, integral with the folded and doubled imperforate elastic brim B, which forms a 35 water-tight joint around the head of the wearer, substantially as described.

In testimony whereof I have hereunto set my hand and seal in the presence of two subscribing witnesses.

WILLIAM OSBORNE. [L. S.]
